(57) **CLAIM**

The ornamental design for a drinking straw holding device with display arrangement, as shown and described.

DESCRIPTION

FIG. 1 is a front elevational view of a drinking straw holding device with display arrangement according to my new design;

FIG. 2 is a bottom plan view thereof;

FIG. 3 is a top plan view thereof;

FIG. 4 is one side elevational view thereof;

FIG. 5 is a rear elevational view thereof;

FIG. 6 is another side elevational view thereof;

FIG. 7 is a cross-sectional view according to sectional line 7-7 of FIG. 5;

FIG. 8 is a rear perspective view thereof;

FIG. 9 is another rear perspective view thereof;

FIG. 10 is a further rear perspective view thereof; and,

FIG. 11 is a front perspective view thereof.
